(57) **CLAIM**

The ornamental design for a hip brace, as shown and described.

DESCRIPTION

FIG. 1 is a front elevation view of a hip brace shown in a first configuration with the upper strap detached;

FIG. 2 is a rear elevation view thereof;

FIG. 3 is a front elevation view of the hip brace of FIG. 1 shown in a second configuration with the upper strap attached to the left side;

FIG. 4 is a rear elevation view thereof;

FIG. 5 is a front elevation view of the hip brace of FIG. 1, shown in a third configuration with the upper strap attached to the right side; and,

FIG. 6 is a rear elevation view thereof.

The broken lines on the front surface depict portions of the hip brace that form no part of the claimed design. The broken lines showing hook-and-loop fasteners on the rear

(Continued)

surface depict elements of the hip brace that form no part of the claimed design. All broken lines form no part of the claim.

1 Claim, 6 Drawing Sheets
